UNITED STATES PATENT OFFICE.

IRA M. POSTON, OF DALLAS, TEXAS.

ELEVATOR GATE.

Application filed October 25, 1926. Serial No. 143,818.

This invention relates to new and useful improvements in elevator gates.

The object of the invention is to provide a gate comprising telescoping sections suspended by differential flexible connections, whereby said sections telescope as the gate is elevated, thus permitting the gate to be used in opening with a limited overhead clearance.

10 A construction designed to carry out the invention will be hereinafter described, together with other features of the invention.

The invention will be more readily understood from a reading of the following specification and by reference to the accompanying drawings, in which an example of the invention is shown and wherein:

Fig. 1 is an elevation of a gate constructed in accordance with my invention, the gate 20 being shown in full lines in its lowered or closed position and in dotted lines in its elevated open position,

Fig. 2 is a vertical sectional view taken on the line 2—2 of Fig. 1,

25 Fig. 3 is a cross-sectional view taken on the line 3—3 of Fig. 1.

In the drawings the numeral 10 designates a gate frame having vertical guideways 11 on each side. A pair of gate sections 30 12 and 13 are mounted to slide vertically in these guideways.

The lower section 12 comprises a transverse bottom bar 14 connected with a transverse top rail 15 by vertical spaced slats or stays 16. The slats 16 extend through vertical slots 17 in the bottom bar 18 of the upper gate section 13, which bar underlies the rail 15.

The upper section 13 comprises vertical 40 slats 19 in staggered relation to the slats 16 extending through slots 20 in the top rail 15 of the lower section 12. The slats 19 support a top rail 21. The sections may be telescoped by sliding the rail 15 up the slats 45 19, whereby the slats 16 are slid up through the bar 18.

The rail 15 is secured to the lower end of a rope, cable or other flexible connection 22 which extends up and over a pulley 23 50 depending from the center of the lintel 10' of the gate frame. This rope extends under the lintel, and passes over a pulley 24 in the upper end of a boxing 25 at one side of the frame. The rope hangs in the boxing 55 and has a counterbalancing weight 26 on its lower end.

Differential ropes, cables or the like 27 depend from eye bolts 28 near each end of the lintel 10'. These ropes pass under pulleys 29 mounted on the bottom bar 18 of the 60 upper gate section 13, then up and over pulleys 30 on the top rail 15 of the lower gate section 12. The ends of the ropes are fastened to the bar 18.

It will be seen that as the gate sections 65 are moved upwardly the weight 26 will pull the rope 22 over the pulleys 23 and 24, thus counterbalancing said sections and holding them in the position to which they are moved. The upper gate section 13 being 70 supported only by the loops of the ropes 27 and the pulleys 29 and 30 will be suspended thereby. Thus as the lower section is raised, the upper section will also be elevated, but the loops will elongate owing to 75 the passage of the ropes over the said pulleys.

This action will cause the lower gate section 12 to move faster than the lower gate section 13, whereby the rail 15 and the bar 80 18 will separate, thus causing said sections to telescope and reduce the height of the gate. When the gate reaches its upper limit the sections will have completely telescoped as is shown in dotted lines in Fig. 1. This 85 will raise the bottom bar 14 high enough to give the desired head room, but the gate will occupy considerably less space than when it is open.

Various changes in the size and shape of 90 the different parts, as well as modifications and alterations, may be made within the scope of the appended claims.

What I claim, is:

1. In an elevator gate, a gate frame, a 95 pair of telescoping gate sections mounted to slide vertically in said frame, a flexible connection suspended in the frame and supporting the lower gate section, a counterbalance attached to said connection, other 100 flexible connections suspended from the top of the frame and attached to the upper gate section, and revolving supports on both sections and over which the last named flexible connections are looped.

2. In an elevator gate, a gate frame, a pair of telescoping gate sections mounted to slide vertically in said frame, a flexible connection suspended in the frame and supporting the lower gate section, a counterbalance attached to said connection, other 110 flexible connections suspended from the top

of the frame and attached to the upper gate section, and pulleys mounted on the bottom of the upper section and upon the top of the lower section and over which the last 5 named connections are looped.

3. In an elevator gate, a gate frame, a pair of slatted gate sections, the slats of the lower section telescoping through the bottom bar of the upper section and the slats of 10 the upper section telescoping through the top rail of the lower section, pulleys at the top of the frame, a connection passing over the pulleys and having one end attached to the lower gate section, a counterbalance attached to said connection, other flexible connections having their upper ends attached to the top of the frame and their lower ends attached to the upper gate sections, and pulleys mounted on the sections and over which 15 the last named connections are double-looped.

4. In an elevator gate, a gate frame, a pair of slatted gate sections, the slats of the lower section telescoping through the bottom bar of the upper section and the slats 25 of the upper section telescoping through the top rail of the lower section, pulleys at the top of the frame, a connection passing over the pulleys and having one end attached to the lower gate section, a counterbalance attached to said connection, other flexible connections having their upper ends attached to the top of the frame and their 30 lower ends secured to the bottom of the upper gate section, pulleys mounted on the bottom bar of the upper section and upon the top rail of the lower section and over which the last named connections are double-looped.

In testimony whereof I affix my signature.

IR A. M. POSTON.
